UNITED STATES PATENT OFFICE

CHESTER J. DU MOND, OF JERSEY CITY, NEW JERSEY

BUOYANT DRUM FOR MOTOR PONTOONS

Application filed April 4, 1927. Serial No. 180,845.

This invention relates to buoyant drums for motor pontoons and is an improvement over my U. S. Letters Patent #1,360,101.

One of the principal objects of this invention is to improve the floatability of the drum by dividing the interior of the same into eight separate compartments and which greatly strengthens the construction thereof.

Another object of the invention is to provide a buoyant drum having radially arranged paddles provided on the periphery thereof and which are much stronger and durable than those heretofore used for this purpose, and they further produce a more positive propelling action when in use.

A further object is the provision of a buoyant drum having equi-distantly spaced paddles mounted thereon, each of which has a front face disposed in alignment with the axis of the drum to take a firm hold in the water when the drum is rotating in a forward direction, and a rear or back face disposed at an acute angle with respect to the front face, which provides a partial resistance to the body of water when the drum is rotated in a reverse direction when bringing the pontoons to a stop when it is moving in a forward direction under its own momentum.

With these and other objects in view, the invention resides in certain novel construction and arrangement of parts, the essential features of which are hereinafter fully described, are particularly pointed out in the appended claims, and are illustrated in the accompanying drawings, in which:—

Figure 1 is a side elevation of my improved pontoon drum.

Figure 2 is a vertical transverse sectional view on the line 2—2 of Figure 1.

Figure 3 is a vertical sectional view taken at right angles to Figure 2.

Figure 4 is a sectional perspective view through one of the paddles.

Referring more particularly to the drawings, the reference numeral 10 designates my improved pontoon drum in its entirety and which includes an annular wall or cylinder 11 of a given diameter and which has angle irons 12 extending about its inner face at the side edges thereof. The angle irons 12 are

riveted or welded to the annular wall 11 to be rigidly fastened thereto. Bolted or riveted to the angle irons 12 are heads or end disks 13 which seal the ends of the drum to prevent water from seeping into the interior thereof. A shaft 14 extends axially through the ends walls and has the drum keyed thereto for rotation therewith when the shaft is mounted in bearings for operation.

Fixed to the inner face of the annular wall 11 midway between the end walls 13 is a T-iron 15, the cross head of which fits flat against the inner walls of the annular wall 11, while the inwardly extending flange serves as a support for a central wall or partition 16, which is riveted or welded to the T-iron to form an integral part of the drum. The partition 16 divides the drum into two separate compartments and they in turn are each divided into four separate compartments by four partitions 17 of general dihedral configuration, which have their adjacent flat faces engaging each other to provide separate compartments 18. The partitions 17, there being eight altogether, are secured to the inwardly extending flanges of angle irons 19 of a shape similar to the configuration of the partitions 17, and which are fixedly mounted on opposite sides of the central partition 16 and on the inner faces of the end walls 13. The curvilinear portions of the partitions 17 are disposed diametrically opposite each other to provide a compartment 19' through which the shaft 14 passes. From the description thus far, it will be seen that I have provided a strong and durable construction of drum which will withstand considerable strain without damage. By dividing the interior of the drum by the central partition 16, I strengthen the drum midway between its ends, and further divide the interior of the drum into eight separate watertight compartments. Should a leak or break occur in the peripheral wall of the drum or in the end wall of the same, the same will not materially affect the buoyancy of the drum, as the remainder of the compartments are capable of keeping the same afloat.

Mounted transversely of the outer periphery of the drum and arranged in suitable

spaced relation to each other, are paddles 20 of a novel construction. Each paddle comprises a front plate 21 having an angularly disposed flange 21'. An angle iron 32 over-
 5 lies the flange 21' while rivets 22 pass through the angle iron, flange and wall 11 to secure the parts in position. The plate 21 extends radially from the drum in alignment with the axis of the same. Riveted to the annular wall 11 rearward of the plate 21 is a rear plate 23 having its longitudinal edges offset to provide flanges 24 and 25, the flanges 25 being disposed parallel to the plate 21 but is spaced therefrom by a strip 26. Rivets pass through
 10 the angularly disposed flange 25, strip 26 and plate 21 to securely fasten these parts together. The flange 24 rests upon the annular wall 11 rearward of the plate 21, and is held thereagainst by an angle iron 24', through
 15 which rivets 25' pass. A substantially U-shaped brace member 27 is riveted to the plates 21 and 23 to keep the same in spaced relation and strengthen the same. Any number of paddles may be provided on the drum,
 20 depending upon the diameter of the same.

By constructing a paddle of this kind, the same will provide a surface which will dig into the body of water when the drum is rotating in a forward direction, but owing to
 25 the pitch of the back of the paddle only a slight resistance to the water is set up upon the reverse or backward rotation of the drum, and which will be found most efficient when bringing the pontoon to a gradual and quick stop when moving forward under its own momentum.

The end plates or disks 13 may have manholes or openings 28 therein, which enter into the respective compartments but which are
 30 normally sealed by a closure plate 29 which is welded to the disks as at 30. Should it become necessary to gain access to the compartments to repair any damage parts on the interior of the drum, the plate may be removed and access to the interior may be had through the opening 28.

Removable drain plugs 31 are provided in the annular wall 11 for draining any water which might accumulate in the respective
 35 compartments.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

60 What is claimed as new is:-

1. In a pontoon propeller comprising a buoyant drum, paddles extending lengthwise of the periphery of said drum and equi-distantly spaced therearound, each of
 65 said paddles including a front plate having

an angularly disposed flange resting upon said drum, an angle bar disposed over said flange and riveted thereto and to said drum and front plate, a rear plate having offset flanges along its longitudinal edges, one of which rests upon said drum and the other against a strip interposed between the outer end of said front plate and said last flange, rivets passing through said last flange, strip, and front plate to hold the same together, 70 an angle iron seated against the lower flange and back plate and riveted thereto and to said drum, and a brace member interposed between said front and back plates for maintaining said back plate at an acute 75 angle with respect to said front plate.

2. In a revolvable pontoon drum having a transversely disposed hollow cylindrical wall, paddles arranged in spaced relation about the exterior of said wall, each of said paddles including a front plate and provided with a base flange, said flange attached on the periphery of said wall, said plate adapted to attack the supporting water on revolution of the drum, and a rear supporting plate mounted on said front plate and having also a flange attached on the periphery of said wall.

In testimony whereof I have affixed my signature.

CHESTER J. DU MOND.
